UNITED STATES PATENT OFFICE.

JOSEPH I. HIGGINS, OF EAST ROCKAWAY, NEW YORK.

FOLDING BED.

1,137,402.

Specification of Letters Patent. Patented Apr. 27, 1915.

Application filed July 21, 1913, Serial No. 780,195. Renewed September 19, 1914. Serial No. 862,596.

To all whom it may concern:

Be it known that I, JOSEPH I. HIGGINS, a citizen of the United States, and a resident of East Rockaway, in the county of Nassau and State of New York, have invented a new and Improved Folding Bed, of which the following is a full, clear, and exact description.

The invention relates to the so called man-
tel beds and its object is to provide a new
and improved folding bed arranged to per-
mit of conveniently swinging the bed down-
ward into extended position for use, or up-
ward into vertical position against a wall or
other support to occupy a minimum amount
of space in the room, at the same time giving
a wardrobe appearance to the bed and providing a shelf for supporting ornamental
or other articles.

For the purpose mentioned use is made
of a spring frame provided with side bars,
floor brackets provided with bearings en-
gaged by one of the said side bars to permit
of swinging the spring frame from hori-
zontal into vertical folded position or vice
versa, side bar brackets attached to the other
side bar, and legs pivoted on the said side
bar brackets and adapted to rest on the floor
at the time the bed is in a horizontal posi-
tion, the said legs being adapted to hang in
a vertical position at the time the spring
frame is swung upward into vertical folded
position.

Figure 1 is a perspective view of the fold-
ing bed in vertical folded position and
showing the curtain partly drawn back;
Fig. 2 is a cross section of the same on
the line 2—2 of Fig. 1; Fig. 3 is an en-
larged elevation of one of the floor brackets;
Fig. 4 is an enlarged view of one of the legs
and its shelf bracket, and Fig. 5 is a sec-
tional plan view of the bed on the line 5—5
of Fig. 1.

The spring frame A of the bed is of the
usual construction and is provided with a
suitable bed spring B adapted to support
the mattress C of the bed. The spring frame
A is further provided with the usual side
bars D, D', of which the side bar D is the
rear side bar and engages open bearings E'
formed on the upper ends of floor brackets
E attached to the floor F adjacent to a wall
F' or other support, as indicated in Figs. 1
and 2. On the side bar D', which is lo-
cated at the front side of the bed, are
clamped brackets G each preferably formed

of two parts G', G² connected with each
other by a pivot G³ (see Fig. 4) to permit
of opening and closing the bracket to allow
of placing the same conveniently in position
on the side bar D'. The free ends of the
bracket parts G', G² are adapted to be fas-
tened together by a bolt G⁴ to securely draw
the parts G' and G² in clamping contact with
the side bar D' with a view to securely fas-
ten the brackets G to the said side bar D'.
60

The bracket part G' of each bracket G is
provided with an integral lug G⁵ which
carries a pivot H' for a leg H to swing on,
so that the leg H stands at an angle to the
spring frame A and rests on the floor F at
the time the bed is in extended position, see
dotted lines in Fig. 2, or the said leg hangs
down parallel with the spring frame A at
the time the bed is swung upward into ver-
tical folded position as shown in full lines
in Figs. 1 and 2. The heel end H² of each
leg H is beveled and adapted to abut against
the exterior portion of the bracket part G'
at the time the spring frame A is in hori-
zontal position, so that each leg H is prac-
tically locked in extended position.
70

Each bracket part G' is further provided
with a lug G⁶ at a right angle to the lug G⁵
and terminating in an attaching member G⁷
to which is secured a shelf I preferably in
the form of the side rail of an ordinary bed-
stead so as to give the bed the proper ap-
pearance when in use. It is understood that
the shelf I extends in a vertical plane at the
time the bed is in extended position for use,
as indicated by dotted lines in Fig. 2, but
when the bed is in folded vertical position
the shelf I extends horizontally over the
top of the bed to form a support for orna-
ments or other articles.
80

A curtain rod J of approximately U-shaped
form extends along the front edge of the
ends of the shelf I, and is secured at its ter-
minals by brackets J' to the said shelf I.
The curtain rod J is engaged by rings K' of
a two-part curtain K adapted to be drawn
along the curtain rod into a closed position
so as to completely hide or cover up the bed
at the time the latter is in vertical or folded
position. When the bed is to be used for
sleeping purposes the two parts of the cur-
tain shown are drawn apart to the sides of
the bed and are encircled by bands L hooked
or otherwise removably attached to the
spring B or other portion of the bed so that
the folded curtain does not interfere while
100
105
110

swinging the bed from vertical folded position downward into a horizontal extended position.

The mattress C and the bedclothing are adapted to be locked in place by the use of bands N terminating at one end in hooks N' hooking onto the bed spring B, as plainly indicated in Figs. 1 and 2. The other ends of the bands N terminate in single large hooks N² adapted to hook onto the side bar D' so that the bands N pass over or around the mattress and the bedclothing to securely hold the same in place on the bed springs B.

It is understood that by the arrangement described the side bar D' of the spring frame A can be readily engaged with the bearings E' of the floor brackets E secured to the floor, and it is only necessary for the user to swing the bed either up into a vertical position or down into horizontal position according to the intended use of the bed at the time. It is also understood that when the bed is swung downward into horizontal position the legs H gradually move into a right angled position relative to the spring frame A so as to rest on the floor and thus support the bed with the mattress C the desired distance above the floor. When the bed is to be folded against the wall F it is only necessary for the operator to swing the bed upward so that the side bar D turns in the bearings E' and then the operator can draw the curtain K into closed position to hide the bed at the same time permitting the use of the shelf I for supporting ornamental and other articles. The folding bed shown and described is very simple and durable in construction and composed of comparatively few parts. It will also be noticed that when the bed is in extended position the curtain parts K are folded at the ends of the bed and extend in a transverse direction so as to be completely out of the way, that is, do not interfere when swinging the bed into folded or extended position. It is also understood that the bands N are placed in position immediately prior to swinging the bed from horizontal into vertical position.

Having thus described my invention, I claim as new and desire to secure by Letters Patent.

1. A folding bed, comprising a spring frame provided with side bars, floor brackets provided with bearings engaged by one of the said side bars to permit of swinging the spring frame from a horizontal into a vertical folded position or vice versa, legs pivoted adjacent the other side of the frame and adapted to rest on the floor at the time the spring frame is in horizontal position, and adapted to hang in a vertical position at the time the spring frame is in vertical

folded position, and a shelf carried by, and movable with, the last mentioned frame side 65 and forming a side rail for the bed when the said frame is in extended position.

2. A folding bed, comprising a spring frame provided with side bars, floor brackets provided with bearings engaged by one 70 of the said side bars to permit of swinging the spring frame from a horizontal into a vertical folded position or vice versa, side bar brackets attached to the other side bar, legs pivoted on the said side bar brackets 75 and adapted to rest on the floor at the time the spring frame is in horizontal position, and adapted to hang in a vertical position at the time the spring frame is in vertical folded position, and a shelf attached to the said side bar brackets and adapted to form a side rail for the bed at the time the bed is in extended position.

3. A bed, comprising a spring frame having front and rear side bars, floor brackets 85 adapted to be attached to the floor and having open bearings adapted to be engaged by the said rear side bar, leg brackets each having bearing parts pivotally connected with each other and adapted to engage the front 90 side bar, a bolt connecting the bearing parts with each other to clampingly attach the leg brackets to the said front side bar, each leg bracket having lugs standing at an angle one to the other, a leg pivoted to one of the 95 lugs, and a shelf attached to the other lug.

4. In a shelf bed, the combination of a bed frame having a pivotal support at one side whereby it may be moved from a horizontal to a vertical position and vice-versa, 100 a shelf carried by the opposite side of the frame and forming a side rail for the bed in lowered position, covering curtain members movable along the shelf to conceal the frame in raised position, and means whereby to hold the said curtain members in furled position at the ends of the frame when the latter is lowered, substantially as and for the purpose specified.

5. A bed, comprising a spring frame having front and rear side bars, floor brackets having bearings for the rear side bar and upon which the frame is movable, brackets clamped upon the front side bar and having projections, legs pivoted to certain of the 115 bracket projections, and a shelf rigidly attached to the other bracket projections, substantially as described.

In testimony whereof I have signed my name to this specification in the presence 120 of two subscribing witnesses.

JOSEPH I. HIGGINS.
